UNITED STATES PATENT OFFICE.

GEORGE C. JENSEN, OF OAKLAND, CALIFORNIA.

LEVER-LOCK.

1,307,497.

Specification of Letters Patent. Patented June 24, 1919.

Application filed December 24, 1918. Serial No. 268,192.

To all whom it may concern:

Be it known that I, GEORGE C. JENSEN, a citizen of the United States, residing at Oakland, in the county of Alameda and State of California, have invented certain new and useful Improvements in Lever-Locks, of which the following is a specification.

The present invention relates to an improved construction whereby the shift levers and rods of a motor vehicle transmission mechanism may be locked from use by unauthorized persons.

The invention has for its principal objects to provide a construction wherein the ends 15 of the shifter rods or devices are protected from movement owing to the closing of the outer ends of the bores within which the same operate. To provide a construction wherein the lever is fulcrumed for pivotal movement, and at a point removed from said 20 fulcrum point operates within a guide which is capable of positioning to preclude movement of the lever in its operative plane, thereby preventing the operation of the 25 shifter devices by the lever.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be 30 resorted to without departing from the spirit or sacrificing any of the advantages of the invention.

To more fully comprehend the invention, reference is directed to the accompanying 40 drawings, wherein—

Figure 1 is a view in vertical section of a construction illustrating the preferred embodiment of my invention.

Fig. 2 is a view in top plan view.

Fig. 3 is a sectional view taken on line 45 3—3 of Fig. 1.

Fig. 4 is a view in plan of the lever fulcrum cup seated in its socket and illustrating more particularly the shape of the same.

Fig. 5 is a sectional view taken on line 50 5—5 of Fig. 1, illustrating the spring end which precludes axial rotation of the lever within its fulcrum socket.

Fig. 6 is a sectional view taken on line 55 6—6 of Fig. 1.

Referring more particularly to the draw-

ings, wherein like characters of reference designate corresponding parts, 1 indicate the opposing walls of the member, preferably a gear case provided with the aligned bores 2 60 closed at their outer ends by plugs or disks 3 pressed or otherwise seated therein. In the bores are received the opposite ends of shifter rods or devices 4 and 5 which lie in parallel spaced relation and which are adapted for 65 independent longitudinal movement when actuated by a suitable lever hereinafter described.

Bridging the walls 1 and providing a closure for the top of the case is a cover 6 secured in position by the screws 7 which intersect the path of movement of the shifter rods or devices 4 and 5 and which are provided within their length with the reduced portion 8 with which said rods or devices 4 75 and 5 operate, whereby the rods prevent the removal of the screws from the wall 1 and thereby preclude the removal of the cover from the case. The retaining screw 7 at one end of each rod is so positioned relatively to 80 the end of the rod as to be capable of free insertion in position when its coöperating rod is moved to position the gear controlled thereby in power transmitting relation, and the opposite end of said rod is formed with 85 a recess 9 which permits the seating of the screw at that end of the case in position in its coöperating wall, thus when the rods are in power transmitting position the cover is capable of being removed from the casing 90 but when in neutral position the cover is precluded from removal.

Extending upwardly from the cover is a raised stamping or shell 10, the upper end of which is bent inwardly forming a lever 95 fulcrum socket 11, provided at its base with a circular opening 12 through which extends the lower end 13 of the operating lever 14.

Pressed on or otherwise secured to the lever is a fulcrum cap 15 for reception into 100 the socket 11, the coöperation of said elements providing a fulcrum for the lever which permits of universal swinging movement thereof.

By reference to Fig. 4 it will be observed 105 that the fulcrum cup and socket 15 and 11 are oval in plan, which precludes axial rotation of the lever on its fulcrum.

Threaded, as at 16, to the upper outer surface of the shell 10 is a lever locking 110 member and retainer cap 17 provided with a spherical upper end 18 formed with an

oblong opening 19 therein through which passes and operates the upper end of the lever 14.

The rotation of the cap 17 to a position 5 at right angles from that illustrated in Figs. 1, 2 and 3 of the drawings, positions the oblong opening 19 therein in a plane parallel with the rods or devices 4 and 5, in which position operative movement of the 10 lever 14 on its fulcrum is permitted, the lever being formed at opposite sides in the region of the wall of said opening 19 with depressions 20 which permit of the lateral or selective movement of the lever to engage 15 one of said rods or devices 4 and 5.

On the positioning of the cap 17, as in Figs. 1, 2 and 3 of the drawings, the opening 19 is disposed at right angles to the operative movement of the lever, thus precluding movement of the lever to operate 20 said shifter devices 4 and 5.

Positioned beneath the spherical upper end 18 of the cap 17 and the fulcrum cup 15 is a coiled spring 21 surrounding the 25 lower portion 13 of the lever and secured at its upper end, as at 22, to the retainer member and at its lower end passing through an opening 23 in the cup 15 and extending into a slot 24 in the socket 11, said spring 30 rotating the cap 17 a one-quarter revolution in a clockwise direction from the position disclosed in Figs. 1, 2 and 3 of the drawings.

To preclude movement of the cap 17 from locked to unlocked position, I provide the 35 cap with a bore 25 open at its inner end and arranged at right angles to the shell 10, the bore when the cap is positioned as in the drawings, registering with an opening 26 in the shell 10. Within the bore is positioned 40 an inwardly spring pressed latch 27 provided in its upper surface with a depression 28 in which extends the offset member 29 carried by a rotatable key controlled locking barrel 30 within a casing 31 seated 45 in a depression 32 in an offset 33 formed integral of the cap 17.

On the manual rotation of the cap relatively to the shell and to a position as in the drawings, the latch 27 is automatically 50 projected into the opening 26, thereby locking the cap from rotation on the shell and precluding operative movement of the lever 14. On the withdrawal of the latch 27 from the opening 26 the spring 21 will automatically 55 rotate the cap on the shell in a clockwise direction until such time as the inner end of the latch 27 contacts with the shoulder 34 formed in the shell 10, and which precludes movement in a clockwise direction 60 of the cap on the shell at such time as the oblong opening 19 is disposed in a plane parallel with the shifter rods or devices 4 and 5, at which time the lever 14 is capable of operative movement.

65 If desirable, a dust retaining shell 35 may

be secured to the lever to overlie the spherical upper end 18 of the cap 17 to preclude dust entering through the oblong opening 19. The spring 21 serves to maintain the fulcrum cup 15 seated within the socket 11 and 70 also assists in maintaining the lever in vertical or neutral position.

Having thus described my invention, what I claim as new and desire to protect by Letters Patent is:—

75 1. In combination with a lever, a tubular support through which the lower end thereof extends, the upper end of said support providing a fulcrum socket, a fulcrum cup provided with an opening through which 80 the lever extends, said cup being receivable within said socket, said cup and socket providing a fulcrum for the lever, a cap attached to the tubular support and provided with an opening through which said lever extends and operates, and a spring interposed between the undersurface of said cup and said cap for maintaining said fulcrum members in engaged relation.

85 2. In combination with a lever, a tubular sheet metal support through which the lower end thereof extends, the upper end of said support being bent inwardly providing a fulcrum socket oval in plan, a sheet metal fulcrum cup provided with an opening 90 through which the lever extends, said cup being oval in plan and receivable within said oval socket, said cup and socket providing a fulcrum for the lever, a cap having threaded attachment to the tubular support 100 and provided with an opening through which said lever extends and operates, and a spring interposed between the undersurface of said cup and said cap for maintaining 105 said fulcrum members in engaged relation.

95 3. In combination with a lever, a tubular sheet metal support through which the lower end thereof extends, the upper end of said support being bent inwardly providing a fulcrum socket oval in plan, a sheet metal fulcrum cup provided with an opening 110 through which the lever extends, said cup being oval in plan and receivable within said oval socket, said cup and socket providing a fulcrum for the lever, a cap having threaded attachment to the tubular support and provided with an elongated opening 115 through which said lever extends and which affords a guide for the lever, said cap capable of axial rotation about the lever to position the opening therein to preclude movement of the lever in one direction, and means for locking the cap in its latter position.

120 4. In combination with a lever fulcrumed within its length for swinging movement, a guide positioned a distance from the lever fulcrum point and through which the lever operates, said guide capable of axial move- 125 130

- ment about the lever to preclude operative movement thereof in one direction, and means for locking said guide in its latter position.
5. In combination with a lever fulcrumed within its length for swinging movement and formed on opposite faces with depressions providing a portion thereof elongated in cross section, a member positioned a distance from the lever fulcrum point and provided with an elongated slot within which operates the elongated cross sectional portion of the lever and providing a guide therefor, said elongated cross section of the lever corresponding to the transverse cross section of said slot whereby on the movement of said member to position the guide at right angles to the depressions movement of said lever in one direction will be precluded.
10. In combination with a lever fulcrumed within its length for swinging movement and formed on opposite faces with depressions providing a portion thereof elongated in cross section, a member positioned a distance from the lever fulcrum point and provided with an elongated slot within which operates the elongated cross sectional portion of the lever and providing a guide therefor, said elongated cross section of the lever corresponding to the transverse cross section of said slot whereby on the movement of said member to position the guide at right angles to the depressions movement of said lever in one direction will be precluded.
15. In combination with a lever, a tubular shell through which the same extends and within which it is fulcrumed, a member axially rotatable about said shell and provided with a guide opening through which said lever extends, said member capable of axial movement about said lever to position said guide to preclude movement of the lever in one direction, means for locking said member in its latter position, and means for rotating said member on said shell from its latter position on the release of said locking means.
20. In combination with a lever, a tubular support through which the lower end thereof extends, the upper end of said support providing a fulcrum socket, a fulcrum cup provided with an opening through which the lever extends, said cup being receivable within said socket, said cup and socket providing a fulcrum for the lever, a cap attached to the tubular support and provided with an elongated opening through which said lever extends and which affords a guide for the lever, said cap capable of axial rotation about the lever to position the opening therein to preclude movement of the lever in one direction, and means for locking the cap in its latter position.
25. In combination with a lever, a tubular shell through which the same extends and within which it is fulcrumed, a member axially rotatable about said shell and provided with a guide opening through which said lever extends, said member capable of axial movement about said lever to position said guide to preclude movement of the lever in one direction, means for locking said member in its latter position, and means for rotating said member on said shell from its latter position on the release of said locking means.
30. In combination with a lever, a tubular support through which the lower end thereof extends, the upper end of said support providing a fulcrum socket, a fulcrum cup provided with an opening through which the lever extends, said cup being receivable within said socket, said cup and socket providing a fulcrum for the lever, a cap attached to the tubular support and provided with an elongated opening through which said lever extends and which affords a guide for the lever, said cap capable of axial rotation about the lever to position the opening therein to preclude movement of the lever in one direction, and means for locking the cap in its latter position.
35. In combination with a lever, a tubular support through which the lower end thereof extends, the upper end of said support providing a fulcrum socket, a fulcrum cup provided with an opening through which the lever extends, said cup being receivable within said socket, said cup and socket providing a fulcrum for the lever, a cap attached to the tubular support and provided with an elongated opening through which said lever extends and which affords a guide for the lever, said cap capable of axial rotation about the lever to position the opening therein to preclude movement of the lever in one direction, and means for locking the cap in its latter position.
40. In combination with a lever, a tubular support through which the lower end thereof extends, the upper end of said support providing a fulcrum socket, a fulcrum cup provided with an opening through which the lever extends, said cup being receivable within said socket, said cup and socket providing a fulcrum for the lever, a cap attached to the tubular support and provided with an elongated opening through which said lever extends and which affords a guide for the lever, said cap capable of axial rotation about the lever to position the opening therein to preclude movement of the lever in one direction, and means for locking the cap in its latter position.
45. In combination with a lever, a tubular support through which the lower end thereof extends, the upper end of said support providing a fulcrum socket, a fulcrum cup provided with an opening through which the lever extends, said cup being receivable within said socket, said cup and socket providing a fulcrum for the lever, a cap attached to the tubular support and provided with an elongated opening through which said lever extends and which affords a guide for the lever, said cap capable of axial rotation about the lever to position the opening therein to preclude movement of the lever in one direction, and means for locking the cap in its latter position.

In testimony whereof I have signed my name to this specification in the presence of a subscribing witness.

GEORGE C. JENSEN.
